DESCRIPTION

FIG. 1 depicts a perspective view of an electrical adapter for neurostimulation leads. A lead body and terminal contracts are shown in broken lines extending away from the electrical adapter and the broken lines are provided for environmental purposes and form no part of the claimed design;

FIG. 2 depicts a front view of the electrical adapter;

FIG. 3 depicts a rear view of the electrical adapter;

FIG. 4 depicts a first later view of the electrical adapter;

FIG. 5 depicts a second lateral view of the electrical adapter;

FIG. 6 depicts a top of the electrical adapter; and,

FIG. 7 depicts a bottom view of the electrical adapter.

Although references to the drawings have been made with respect to lateral, top, bottom, rear, and front, it shall be appreciated that the forgoing orientations are used for reference purposes only and the model of the present invention may be disposed in any orientation.

The broken lines shown are included for the purpose of illustrating portions of the electrical adapter for neurostimulation leads that form no part of the claimed design.
